UNITED STATES PATENT OFFICE

2,584,708

PORTABLE VENDING MACHINE

Wallace A. Jenkins, Lakewood, Ohio, assignor to
The Atlas Manufacturing and Sales Company,
Cleveland, Ohio

Application July 28, 1947, Serial No. 764,055

3 Claims. (Cl. 220—4)

1

This invention relates to coin operated portable vending machines and particularly to portable machines adaptable for dispensing a measured quantity of bulk articles such as nuts or candy.

The primary object of the invention is to provide a small light weight machine that may be easily carried and placed on a cafe table and which occupies relatively little table space.

Another object is to construct such machine so that its separable parts may be firmly held together and so that its contents may be locked in and be retained against unauthorized access.

A further object is to make a device of the type stated which may be easily refilled and from which deposited coins may be quickly and easily removed by authorized persons.

These and other objects of the invention will become apparent from a reading of the following specification and claims, together with the accompanying drawing in which like parts are referred to and indicated by like reference characters and wherein:

Figure 1 is a right side elevation of the portable vending machine constituting this invention and completely assembled;

Figure 2 is a rear view thereof with portions broken away to show construction;

Figure 3 is an exploded view thereof;

Figure 4 is an enlarged sectional view of a part of the cover and clamp members;

Figure 5 is an enlarged sectional view of portions of the body and clamp members;

Figure 6 is an enlarged sectional view of a part of the body, clamp and lock members, the lock being in the open condition; and

Figure 7 is a view similar to that of Figure 6 but showing the members in locked condition.

In the drawing, there is shown a portable vending machine made in accordance with this invention and which has a body, broadly indicated by the reference character 10, a commodity container 30, a clamp 40 and a lock 50. Each of these members will be described in detail herein-after and in the order stated.

The following is a list of reference characters used to indicate the important parts or elements forming the aforesaid members.

- 10, body
- 11, body, bottom
- 12, body, bottom, tray
- 13, body, bottom, tray screws
- 14, body, bottom, recess for clamp foot #44
- 15, body, bottom, flange forming shoulder for top seat #24
- 17, body, top
- 18, body, top, measuring apparatus
- 19, body, top, measuring apparatus, coin slot
- 21, body, top, measuring apparatus, operating knob
- 22, body, top, dispensing chute
- 23, body, top, dispensing chute, lid (alternate position of 23a)

2

- 24, body, top, flange forming seat for bottom shoulder #15
- 25, body, top, flange forming shoulder for container seat #31
- 26, body, top, threaded hole for lock
- 30, container
- 31, container, flange, forming seat for shoulder #25
- 32, container, flange forming shoulder for cover
- 34, container, cover
- 35, container, cover, central socket
- 36, container, cover, flange engaging shoulder #32
- 40, clamp
- 41, clamp, handle
- 42, clamp, arm
- 43, clamp, arm, peg in socket #35
- 44, clamp, foot in recess #14
- 45, clamp, hole for lock
- 46, clamp, hole for lock, grooves in engaging lock pins
- 50, lock
- 51, lock, threaded end in hole #26
- 52, lock, cylinder in hole #45
- 53, lock, pins in groove #46
- 54, lock, flange for retaining clamp
- 55, lock, key

The body 10 is made of cast metal and consists of two separable parts, a bottom part 11 and a top part 17. The bottom part 11 is a cup-like element that has a flat base which is attached to the tray 12 by means of the small screws 13. It is cut away at the front and side as shown to fit and receive the hereinafter described measuring apparatus 18 and the dispenser chute 22 which are built into the top part 17. The top brim of the lower body has a flange 15 which forms a small internal shoulder which engages the bottom of the top part of the body. The rear base of the bottom part 11, the portion proximate to the tray 12, is recessed to receive the foot of the hereinafter described clamp member 40.

The top part 17 of the body contains the operating and dispensing mechanism which is conventional and well known in the art. This mechanism is not shown or described in detail, since it is only incidental to the specific invention claimed here. The top part resembles an inverted cup, the bottom brim of which has a flange 24 which forms a small seat. This flange and seat fit neatly and engage the aforesaid shoulder and flange 15 of the bottom 11.

The commodity measuring apparatus indicated by the reference character 18 has a coin slot 19. The measuring and dispensing mechanism operating knob is indicated by the reference character 21. Upon the deposit of a proper coin in the slot 19 and upon turning the knob 21, a measured quantity of goods is dropped from the container 30 into the dispensing chute 22. This chute is provided with a hinged lid 23, which may be raised as indicated by the reference character 23a and

the goods dropped either into the palm of the hand or upon the tray 12.

The top of the part 17 is open and the brim formed by the opening has a flange 25 therearound which forms another small shoulder as shown in the drawing.

The rear of the top part 17 has a threaded hole 26 therein which receives the hereinafter described lock member 50.

The container 30 is simply a glass globe, open at the top and bottom. The bottom of the globe has a flange 31 therearound which forms a small seat and engages the flange 25 and shoulder of the top element 17. The top of the globe has a similar flange 32 which engages the cover 34.

The cover 34 may be made of stamped or cast metal and has a circumferential depending flange or head 36 which engages the flange 32 of the container. This cover is also formed to have a small central recess or socket 35 which receives a part of the hereinafter described clamp 40.

The clamp 40 is made of metal and has a small handle 41 which forms a convenient grip to facilitate carrying this portable machine. The clamp is shaped to conform to the shape of the assembled body and container members and has an arm 42 extending forwardly and over the cover 34. This arm 42 has a small depending pin or peg 43 which fits into the socket 35. The lower part of the clamp 40 has a foot 44 which rests on the tray 12 and fits into the recess 14. About midway between the arm 42 and the foot 44 there is a hole 45 which receives the lock member 50. This hole is aligned with the aforementioned threaded hole 26. The inner wall of this hole 44 has one or more circumferential grooves 46 which engage the pins or tumblers of the lock 50 as shown in the Figure 7.

The lock member 50 consists of a pluglike element threaded at the end 51 to screw into the threaded hole 26 of the body. The lock cylinder 52 fits into the hole 45 of the clamp. The key 55, when inserted into the lock, causes the pins 53 to be drawn inward so that the periphery of the cylinder 52 is smooth. With the key 55 serving as a screw-driver or tool, the lock is inserted into the aligned holes 26 and 45 and screwed in place. When fully inserted, the key is removed and the tumblers 53 are caused to project outward and into the groove or grooves 46. When the pins are so projected, the clamp is held in place firmly by the small flange 54 on the lock which is close to the keyway. The only way the device can be disassembled is by removing the lock plug with a proper key.

When refilling the container with goods, only the lock 50, the clamp 40 and cover 34 are removed; but when removing the coins deposited in the bottom part of the body, the top element 17 must also be removed.

This portable vending machine, as actually made, is only about ten inches high and the container holds about two pounds of nuts. It must therefore be more frequently refilled than other larger vending machines and the structure herein described and claimed facilitates the more frequent refilling with little loss of time.

It should be noted also that the container member may be easily cleaned, thus further enhancing its value as good appearance and sanitation are highly desirable in devices of this nature.

Having thus described the invention in its

preferred form, it is to be understood that the specific embodiments thereof as described and illustrated herein are not to be taken in a limited sense as there may be other forms or modifications of the invention which should also be construed to come within the scope of the appended claims.

I claim:

1. A portable vending machine, comprising in combination, a body member including a tray, the said body member having a recess proximate the lower edge thereof at the said tray and forming with the upper surface thereof a socket, a container member including a cover supported by the body member and a unitary clamp member having a foot portion engageable with the said body member socket, a finger portion engageable with the said container member cover and locking means intermediate the said foot and finger portion engageable with the upper portion of the said body and adapted to releasably secure the several parts together.

2. A portable vending machine, comprising in combination, a body member including a tray, the said body member having a recess proximate the lower edge thereof at the said tray and forming with the upper surface thereof a socket, a container member including a cover supported by the body member and a substantially C-shaped clamp member having a foot portion at the lower end thereof engageable with the said body member socket, a finger portion at the upper end thereof engageable with the said container member cover and locking means intermediate the said upper and lower portion engageable with the said body and adapted to releasably secure the several parts together.

3. A portable vending machine, comprising in combination, a body member having commodity measuring and dispensing apparatus and including a supporting tray, the body member also having a recess proximate the lower edge thereof at the said tray, forming with the upper surface thereof a socket, a container member for the commodity to be vended supported by and opening into the body member apparatus and including a cover, and a substantially C-shaped clamp member having a foot portion at the lower end thereof engageable with the said body member socket, a finger portion at the upper end thereof engageable with the said container member cover and locking means intermediate the said upper and lower portion engageable with the said body and adapted to releasably secure the several parts together.

WALLACE A. JENKINS.
